UNITED STATES PATENT OFFICE

147,310

DESIGN FOR PRINTED FABRIC

Ethelle Thompson, Los Angeles, Calif., assignor
to Ethelle, Inc., Los Angeles, Calif., a corpora-
tion of California

Application February 21, 1947, Serial No. 137,089

Term of patent 3½ years

(CL. D92—1)

To all whom it may concern:

Be it known that I, Ethelle Thompson, a citizen of the United States, residing at Los Angeles, in the county of Los Angeles, State of California, have invented a new, original, and ornamental Design for Printed Fabric, of which the following is a specification, reference being had to the accompanying drawing, forming part thereof.

The figure is a plan view of a piece of printed fabric showing my new design, the broken lines outlining a design unit which unit is repeated in regular succession horizontally on the drawing, as indicated.

I claim:

The ornamental design for printed fabric, as shown and described.

ETHELLE THOMPSON.
